CLAIM

The ornamental design for a scroll saw, as shown and described.

DESCRIPTION

FIG. 1 is a front elevational view of a first embodiment of a scroll saw showing my new design;

FIG. 2 is a right side elevational view of the first embodiment;

FIG. 3 is a right side perspective from the rear of the first embodiment;

FIG. 4 is a rear elevational view of the first embodiment;

FIG. 5 is a top plan view of the first embodiment;

FIG. 6 is a left side perspective view from the front of the first embodiment;

FIG. 7 is a left side elevational view of the first embodiment;

FIG. 8 is a top plan view of a second embodiment of a scroll saw showing my new design with an air hose attached;

FIG. 9 is a front elevational view of the second embodiment;

FIG. 10 is a left side elevational view of the second embodiment;

FIG. 11 is a left side perspective view from the front of the second embodiment; and,

FIG. 12 is a front elevational view of a third embodiment of a scroll saw showing my new design with the blade removed.

All non-shown views of the second and third embodiments are the same as those views shown in figure drawings 1-7.
